UNITED STATES PATENT OFFICE

149,991

DESIGN FOR A DISPLAY CASE

Albert M. Travis, Kansas City, Kans., assignor to John C. Hockery, Kansas City, Mo., trustee for
Henry J. Talge and Foster L. Talge

Application March 12, 1948, Serial No. 145,055

Term of patent 14 years

(Cl. D80—11)

To all whom it may concern:

Be it known that I, Albert M. Travis, a citizen of the United States, residing at Kansas City, in the county of Wyandotte and State of Kansas, have invented a new, original, and ornamental Design for a Display Case, of which the following is a specification, reference being had to the accompanying drawing, forming part thereof, in which the single figure of the drawing is a perspective view of a display case, showing my new design.

The opposite end and side are substantially identical to those shown.

I claim:

The ornamental design for a display case, substantially as shown and described.

ALBERT M. TRAVIS.
